UNITED STATES PATENT OFFICE.

WILLIAM SMITH REYNOLDS, OF GREENWICH, CONNECTICUT.

BOOK-CLAMP.

SPECIFICATION forming part of Letters Patent No. 576,824, dated February 9, 1897.

Application filed February 15, 1896. Serial No. 579,351. (No model.)

To all whom it may concern:

Be it known that I, WILLIAM SMITH REYNOLDS, a citizen of the United States, and a resident of Greenwich, in the county of Fairfield and State of Connecticut, have invented 5 certain new and useful Improvements in Book-Clamps, of which the following is a specification, reference being had to the accompanying drawings, forming a part thereof, in which 10 similar letters of reference indicate corresponding parts.

This invention relates to book-clamps, and the object thereof is to provide an improved device of this class by means of which a record-book of any kind or character may be held open at any desired point and the leaves thereof extended, a further object being to 15 provide a book-clamp which is applicable to any book, and which may be applied thereto 20 for the purpose above mentioned.

The invention is fully disclosed in the following specification, of which the accompanying drawings form a part, in which—

Figure 1 is a plan view of an open book provided with my improvement, and Fig. 2 a side view thereof.

In the practice of my invention I provide a clamp consisting of a rod A, having a flat arm or jaw a, which extends at right angles there- 30 to, and which is provided at the opposite end with a head a², and mounted thereon is a clamp B, having a jaw b, which is provided with a cross-head b², and the clamp B is also provided with an extension b³, which projects 35 in line with the jaw b, and the rod A is passed through the jaw b and the extension b³, adjacent to the body portion of the clamp, as clearly shown in Fig. 2.

Mounted upon the rod A, between the head 40 a² thereof and the extension b³ of the clamp B, is an expansive spiral spring C, and the operation will be readily understood from the

foregoing description when taken in connection with the accompanying drawings.

The clamp B is pressed upwardly against 45 the spring C, so as to separate the jaws b and a, and the device is applied to the book D in the manner shown in Fig. 1, so that the separate jaws b and a cross the central fold thereof and the spring C operates to force the jaw 50 b in the direction of the jaw a and thus securely hold the book in the position shown.

It is evident that the book D may be opened at any desired point and the clamp applied thereto, as described, and it is also apparent 55 that this device may be applied to any form, kind, or class of a book, and my invention is not limited to the exact form of the book-clamp herein described, and I reserve the right to make all such alterations therein and 60 modifications thereof as fairly come within the scope of the invention.

Having fully described my invention, I claim as new and desire to secure by Letters Patent—

65 The herein-described clamp for books, consisting of a rod A provided at one end with a head a², and having the other end bent at right angles, and a sliding clamp B having a head b² provided with an opening through 70 which the rod A passes, and having an arm b bent at right angles thereto, and provided with an opening adapted to receive the arm A, and a spring mounted upon said arm A between the heads a² and b², and adapted to 75 force the arm b upon the arm a, as set forth.

In testimony that I claim the foregoing as my invention I have signed my name, in presence of the subscribing witnesses, this 12th day of February, 1896.

WILLIAM SMITH REYNOLDS.

Witnesses:

JACOB RIPPEL,
HENRY SCHIFFENDECKER.
